UNITED STATES PATENT OFFICE.

JOHN S. SPENCER, OF NEW YORK, N. Y.

DESIGN FOR AN EYEGLASS-CASE.

SPECIFICATION forming part of Design No. 26,394, dated December 15, 1896.

Application filed November 4, 1896. Serial No. 611,083. Term of patent 14 years.

To all whom it may concern:

Be it known that I, JOHN S. SPENCER, a citizen of the United States, residing at the city of New York, in the county and State of New York, have invented and produced a new and original Design for an Eyeglass-Case, of which the following is a specification, reference being had to the accompanying drawings, forming part hereof, and in which—

10 Figure 1 is a top view of an eyeglass-case incorporating my design. Fig. 2 is a longitudinal section of same on the dotted line 2 2 of Fig. 1. Fig. 3 is a transverse section of same on the dotted line 3 3 of Fig. 1; and Fig. 15 4 is a like section of the top of same, the covering being omitted.

The leading features of my design consist of the external form or configuration of the eyeglass-case, whereby a case of attractive appearance is presented, as shown in the accompanying drawings.

In the drawings, A designates the top of the case, and B the bottom thereof, these parts, as usual, being hinged together and provided 25 with a clasp C. The cover A comprises the inner metal shell a and the covering b therefor, and the bottom B comprises the inner

metal shell c and its covering d. The shells a c have the form it is intended the finished case shall bear, and being of rigid material 30 preserve said form.

The top or cover A has the edge and surface outlines shown, said cover having the curved raised surfaces increasing in height toward the clasp C and the abruptly-turned 35 surrounding edges e. Adjacent to the clasp C the top or cover A has the distinct depression D, as shown. The line lettered E in Fig. 1 is merely a depressed line formed in the leather covering b and is unimportant. 40

The bottom B has an edge outline corresponding with the outline of the top A, and at its edges said bottom turns abruptly upward to meet and harmonize with the edges of the top A. 45

What I claim is—

The design for an eyeglass-case, substantially as shown and described.

Signed at New York, in the county and State of New York, this 2d day of November, 1896. 50
JOHN S. SPENCER.
